(57) **CLAIM**

The ornamental design for a tray, as shown and described.

DESCRIPTION

FIG. 1 is a top perspective view of a tray showing our new design;

FIG. 2 is a bottom perspective view of the tray shown in FIG. 1;

FIG. 3 is a front elevation view of the tray shown in FIG. 1, where the rear elevation view is a mirror image thereof;

FIG. 4 is a right side elevation view of the tray shown in FIG. 1, where the left side elevation view is a mirror image thereof;

FIG. 5 is a cross-sectional side elevation view of the tray taken along line 5-5 of FIG. 1;

FIG. 6 is a top plan view of the tray shown in FIG. 1; and,

FIG. 7 is a bottom plan view of the tray shown in FIG. 1.

The broken lines in the figures illustrate portions of the tray that form no part of the claimed design.

1 Claim, 7 Drawing Sheets
